[57] CLAIM

The ornamental design for a holder for a flower or candle, as shown.

DESCRIPTION

FIG. 1 is a front perspective view of the holder for a flower or candle showing my new design, as embodied
in a flower holder;

FIG. 2 is a rear view thereof;

FIG. 3 is a top view thereof;

FIG. 4 is a bottom view thereof;

FIG. 5 is a front perspective view of the holder of my design as embodied in a candle holder, the second embodiment being identical to the first accept for the addition of the candle cup.
